COOLING PLATE FOR BLAST FURNACE
INWALLS AND MANTLESJames L. Wick, Jr., Youngstown, Ohio, assignor
to The Falcon Bronze Company, Youngstown,
Ohio

Application May 27, 1941, Serial No. 395,323

2 Claims. (Cl. 122—6)

This invention relates to metallurgical blast furnaces and more particularly to the water-cooled plates which are conventionally used to cool the upper portion of the shaft or stack of the furnace. The shaft or stack of the furnace rests upon the mantle and is frequently referred to as the "inwall." Together with the mantle, the inwall is cooled by hollow water-cooled plates which are buried within the refractory brickwork of which these portions of the furnace are composed. Ordinarily, the hollow water-cooled plates for cooling the inwall and mantle are shaped like segments of cylinders to conform to the circular contour of the wall of the inwall or mantle of the furnace; and they provide integrally formed necks which project through the refractory brickwork to the exterior thereof to thus provide means for circulating the cooling water.

Due to the fact that a conventional inwall or mantle plate is buried within the refractory brickwork, it is not removable, and when rendered inoperative is usually filled with cement or the like, and its use as a cooling medium discontinued. In case of failure, it is usually found that the integral elongated neck portions which extend from the body portion of the plate are the source of trouble, while the said body portion would otherwise be capable of further duty. Due to the high temperatures to which the inwall and mantle are exposed, there results substantial relative movement between the refractory brickwork and the body portion of the inwall or mantle plate; and this movement causes the cracking of the integral elongated neck portions, whereby they will no longer efficiently conduct water and are thereby rendered inoperative. This situation is totally different from that which is encountered in the bosh of the furnace, wherein the water-cooled bosh plates are usually considerably smaller than inwall or mantle plates and are not buried within the refractory brickwork of the furnace shaft or stack, but are disposed in cavities from which they may be removed and replaced in case of damage.

In patent application Serial No. 193,493, filed March 2, 1938, entitled "Cooling plate for blast furnace inwalls and mantles," of which, together with Louis M. Nesselbush, I am co-applicant, there is disclosed and claimed within that portion of the refractory stack extending above the mantle a hollow cooling plate embodying fluid intake and fluid outlet connections which terminate inwardly of the exterior wall of the stack, together with protection pipes which are dis-

posed in passages extending to the exterior wall of the stack and connected to the cooling plate in such manner as to provide some flexibility between the pipe and cooling plate, fluid inlet and fluid outlet conduits extending through the protection pipes and detachably secured to the respective connections on the hollow cooling plate whereby the conduits may be easily replaced when damaged. The flexibility described accommodates relative movement, with the result that there is no breakage of the protection pipes where they connect with the body portion of the plate. The fluid intake and outlet conduits which extend through these protection pipes may easily be replaced if desired by detaching them, rethreading the body portion of the plate if necessary, and then attaching new conduits. Such construction obviates the necessity of abandoning inwall or mantle plates when only their water connections have failed.

It is among the objects of the present invention to provide an inwall or mantle plate for metallurgical blast furnaces which embodies the readily replaceable water connections of the co-pending application referred to hereinbefore, but utilizing in combination therewith protection pipes therefor which, although susceptible of rigid connection to the body portion of the plate, permit of deflection to accommodate changes accruing from expansion and contraction. Such construction enables the protection pipes to be welded, pinned, screw-threaded or otherwise connected to the body portion of the plate, either in the shop or in the field, whereby the possibility of detachment thereof is eliminated.

To the accomplishment of these and other desirable objects and purposes, I have designed the present, preferred embodiments of the invention presented in the accompanying drawing forming a part of this specification and to which reference should be had in connection with the following detailed description, and in the drawing, for simplicity, like reference numerals have been employed to designate the same parts throughout the several views.

In the drawing:

Figure 1 is a sectional plan of the device of the present invention as embodied in the inwall or mantle of a metallurgical blast furnace, the said inwall or mantle being shown fragmentarily.

Figure 2 is an enlarged sectional view on the line II—II of Figure 1.

Referring more particularly to the drawing, the numeral 1 designates the shaft or stack of a conventional metallurgical blast furnace. As

previously mentioned, this shaft or stack includes the inwall of the furnace which rests upon the mantle (not shown). Beneath the mantle are the bosh and hearth or crucible.

The inwall or mantle plate of the invention is shown at 2 as comprising a large relatively flat hollow body which is substantially rectangular in section and shaped in plan to conform to a segment of a cylinder, thereby providing a concave inner edge 3 and a convex outer edge 4. It will thus be seen how the inwall or mantle plate 2 circulates the cooling water circumferentially of the furnace in the manner long known to those skilled in the art. At suitable locations along the convex outer edge 4 of the inwall or mantle plate 2, water is fed to and from the same by suitable connections which may be placed side-by-side, in remote positions, or otherwise.

As shown in Figure 2, the inwall or mantle plate 2 of the present invention is provided at its water intake and outlet connections with interior boss portions 5 which are apertured and internally screw-threaded, as shown at 6 and 7, respectively. The diameter of the apertures 6 is small as compared with the diameter of the boss portions 5, thereby providing in each instance a wall of substantial thickness. According to this construction, the water inlet and outlet conduits 8 and 9, respectively, may be externally screw-threaded, as shown at 10, and connected directly to the internal screw-threads 6 of the boss portion 5 of the inwall or mantle plate 2. In the event of stripping the threads 6 of the boss portion 5, the latter, due to its substantial wall thickness, may be easily re-threaded. This is of considerable importance due to the very frequent breakage of water conduits adjacent the inwall or mantle plate in the ordinary operation of the blast furnace.

The water intake and outlet connections are provided with exterior boss portions 11 in alignment with the interior boss portions 5.

According to the teachings of the present invention, there is connected to the periphery of each of the exterior boss portions 11 a flexible pipe 12 which extends from the inwall or mantle plate 2 to the exterior of the shaft or stack 1. These flexible pipes 12 form housings for the water intake and outlet conduits 8 and 9, respectively, and serve as guideways for the ready installation or removal of the latter.

The inner ends of the flexible pipes 12 may be secured to the exterior boss portions 11 of the inwall or mantle plate 2 in any suitable manner, as an example of which welding is given, being shown in the drawing at 13. This eliminates the possibility of detachment of the flexible

5 pipes 12 either during the erection of the shaft or stack 1 or subsequent thereto.

The foregoing construction permits considerable deflection to accommodate changes accruing from expansion and contraction during the operation of the blast furnace.

10 While I have shown and described one specific embodiment of the present invention, it will be readily understood by those skilled in the art that I do not wish to be limited exactly thereto, since various modifications may be made without departing from the scope of the invention as defined by the following claims.

I claim:

15 1. In a metallurgical blast furnace comprising a refractory stack extending above the mantle thereof, a hollow cooling plate buried within the wall of said refractory stack whereby refractory portions of the said stack are provided between the inner and outer walls thereof and the said hollow cooling plate, the exterior wall of said stack having a pair of passages communicating with said hollow cooling plate, fluid intake and fluid outlet connections for said hollow cooling plate, each of said connections being in alignment with one of said passages and terminating inwardly of the exterior wall of said stack, a flexible protection pipe disposed in each of said passages and connected to said hollow cooling plate, and fluid inlet and outlet conduits extending through said flexible protection pipes and detachably secured to their respective connections on said hollow cooling plate whereby said conduits may be easily replaced when damaged, etc.

20 2. In a metallurgical blast furnace comprising a refractory stack extending above the mantle thereof, a hollow cooling plate buried within the wall of said refractory stack whereby refractory portions of the said stack are provided between the inner and outer walls thereof and the said hollow cooling plate, the exterior wall of said stack having a pair of passages communicating with said hollow cooling plate for said hollow cooling plate, each of said connections being in alignment with one of said passages and terminating inwardly of the exterior wall of said stack, a flexible protection pipe disposed in each of said passages and connected to said hollow cooling plate, and fluid inlet and outlet conduits extending through said flexible protection pipes and detachably secured to their respective connections on said hollow cooling plate whereby said conduits may be easily replaced when damaged, etc.

25 3. In a metallurgical blast furnace comprising a refractory stack extending above the mantle thereof, a hollow cooling plate buried within the wall of said refractory stack whereby refractory portions of the said stack are provided between the inner and outer walls thereof and the said hollow cooling plate, the exterior wall of said stack having a pair of passages communicating with said hollow cooling plate, a pair of seat means on said hollow cooling plate, fluid intake and fluid outlet connections within said seat means, each of said seat means being in alignment with one of said passages and terminating inwardly of the exterior wall of said stack, a flexible protection pipe disposed in each of said passages and connected to the seat means in alignment therewith, and fluid inlet and outlet conduits extending through said flexible protection pipes and detachably secured to their respective connections on said hollow cooling plate whereby said conduits may be easily replaced when damaged, etc.

30 4. In a metallurgical blast furnace comprising a refractory stack extending above the mantle thereof, a hollow cooling plate buried within the wall of said refractory stack whereby refractory portions of the said stack are provided between the inner and outer walls thereof and the said hollow cooling plate, the exterior wall of said stack having a pair of passages communicating with said hollow cooling plate, a pair of seat means on said hollow cooling plate, fluid intake and fluid outlet connections within said seat means, each of said seat means being in alignment with one of said passages and terminating inwardly of the exterior wall of said stack, a flexible protection pipe disposed in each of said passages and connected to the seat means in alignment therewith, and fluid inlet and outlet conduits extending through said flexible protection pipes and detachably secured to their respective connections on said hollow cooling plate whereby said conduits may be easily replaced when damaged, etc.

35 5. In a metallurgical blast furnace comprising a refractory stack extending above the mantle thereof, a hollow cooling plate buried within the wall of said refractory stack whereby refractory portions of the said stack are provided between the inner and outer walls thereof and the said hollow cooling plate, the exterior wall of said stack having a pair of passages communicating with said hollow cooling plate, a pair of seat means on said hollow cooling plate, fluid intake and fluid outlet connections within said seat means, each of said seat means being in alignment with one of said passages and terminating inwardly of the exterior wall of said stack, a flexible protection pipe disposed in each of said passages and connected to the seat means in alignment therewith, and fluid inlet and outlet conduits extending through said flexible protection pipes and detachably secured to their respective connections on said hollow cooling plate whereby said conduits may be easily replaced when damaged, etc.
